United States Patent Office.

THOMAS DOLAN, OF PHILADELPHIA, PENNSYLVANIA.

Design No. 3,882, dated March 8, 1870.

DESIGN FOR A "BEDOUIN" OR "ARAB."

The Schedule referred to in these Letters Patent and making part of the same.

I, THOMAS DOLAN, of Philadelphia, county of Philadelphia, State of Pennsylvania, have invented or produced a Design for part of a "Bedouin" or "Arab," of which the following is a specification.

Nature of the Design.

My design relates to the shape and configuration of part of the shawl-like garments termed "Bedouins" and "Arabs," and consist of a hood and opening or gap formed and arranged substantially in the manner fully described hereafter.

Description of the Accompanying Drawing.

Figure 1 is a rear view of a "Bedouin" or "Arab" made in accordance with my design, and as it appears when applied to the person, and

Figure 2, a view of the garment as it appears when spread out.

General Description.

The garment consists of two strips, A and A', of knitted or woven fabric, stitched together on the line xx , so as to occupy the relative positions shown in fig. 2.

At the point where the two strips meet their lower corners are cut away, so as to leave an angular gap

or opening, b, the point a of which coincides with the lower point of the diamond-shaped hood B, the apex of the latter terminating at the junction of the upper corners of the two strips A and A'.

Folds may be formed on the upper edges of the strips A and A', and also on the two upper edges of the hood B.

The garment may be ornamented with fringes and tassels to suit the taste of the manufacturer, but these are minor ornaments which form no part of my design, the latter being restricted to the hood, shaped substantially as described, in combination with the opening or gap b.

Claim.

A "Bedouin" or "Arab" having a hood, B, and gap or opening b, formed and arranged substantially as described.

In testimony whereof, I have signed my name to this specification in the presence of two subscribing witnesses.

THOMAS DOLAN.
